UNITED STATES PATENT OFFICE.

HENRY M. CRIPPEN, OF ATHENS, OHIO, ASSIGNOR OF TWO-THIRDS TO FIELD SCOTT AND HARLEY H. HANNING, BOTH OF ATHENS, OHIO.

LOOSE-LEAF-BINDING MACHINE.

1,255,112.

Specification of Letters Patent. Patented Jan. 29, 1918.

Application filed July 13, 1917. Serial No. 180,248.

To all whom it may concern:

Be it known that I, HENRY M. CRIPPEN, a citizen of the United States, residing at Athens, in the county of Athens and State 5 of Ohio, have invented certain new and useful Improvements in Loose-Leaf-Binding Machines, of which the following is a specification.

My invention relates to loose-leaf binding 10 machines.

The objects of the invention are to provide a loose-leaf binding machine in which the perforating punches are adapted to be swung with the perforated leaves thereon 15 over a series of receiving pins upon which the leaves may then be deposited by depressing a follower carried by the punch head. Also to provide means for clamping the perforated sheets while on the pins to a movable sheet carrier adapted to remove the 20 clamped sheets from the receiving pins into a position for readily sewing or securing them together. Also to provide operating means common to the punches and the movable sheet carrier; also to provide means whereby said operating means may operate the punches without operating the sheet carrier; also to provide means whereby the 25 punches, after they have been brought over the receiving pins and deposited the sheets thereon, may assist in the clamping of the sheets to the sheet carrier; also to provide means for holding the sheet carrier and clamp carried thereby in proper position 30 for sewing or securing the clamped sheets together; also to provide an anvil which will retain the punched out material against falling out and littering up the room in which the machine is placed; also to provide 35 an anvil in the form of a tube having series of punch openings so that by changing the position of the anvil a new series of openings may be provided. Further objections and novel features will appear hereinafter.

These objects I accomplish by the construction shown in the accompanying drawings, in which:

Figure 1 is a perspective, partly in section, of my improved loose leaf binding machine with the parts in position for punching.

Fig. 2 is a plan thereof.

Fig. 3 is a sectional side elevation.

Fig. 4 is a sectional side elevation of a 55 portion of the machine on an enlarged scale with the punches entering the anvil.

Fig. 5 is a longitudinal vertical section through the machine with the punches in line with the receiving pins J.

Fig. 6 is a fragmentary sectional view, 60 showing the punches acting on the sheet clamp.

Fig. 7 is a bottom plan of the sheet and clamp carrier.

Fig. 8 is a perspective of the anvil and its 65 closure.

Fig. 9 is a perspective of the sheet clamp.

Fig. 10 is a sectional view, showing the sheet carrier locked in its vertical position to permit sewing or securing the clamped 70 sheets together.

Fig. 11 is a perspective of the casing containing the machine.

The machine casing is in the form of an oblong box and comprises three superposed 75 sections, viz.: the bottom A, open middle section A' hinged at a to the upper rear edge of the bottom A, and top section A² secured when not in use by four long bolts a' passed down through the corners of all 80 three sections and having nuts a² at their threaded ends to firmly bind the sections together. To the ends of the bottom A are pivoted the slotted braces a⁴ engaging with their slots the threaded studs a⁵ on the ends 85 of the open middle section A'; the studs a⁵ having thumb nuts a⁶ and clips a⁷ for clamping the braces a⁴ in their open or closed position. When the machine is in use with the cover A² removed, the middle 90 section A' will be swung upwardly and outwardly and clamped in its vertically disposed position by the thumb nuts a⁶.

B designates two or more letter receiving pins projecting downwardly from the inner 95 side of the free edge of the middle section A' and upon which letters and papers may be impaled temporarily.

C designates a letter or leaf receiving box in open triangular form so that when placed 100 with its apex downwardly on the lower side bar of the middle section A' its upper edge or base may be sprung under the opposite or upper side bar of said section A' and the box be held between said side bars or 105 may be held by pins. Owing to the downwardly converging sides c c of the letter box C, the letters or sheets as thrown into the box will be evened and form an even or regular pile ready for action by the mechanism to be now described. The box C may be held, however, in any desired manner.

This mechanism may be mounted directly in the bottom A of the case, if desired, but as shown it is carried by a base formed of parallel side bars D D bolted as at d d with 5 in the bottom A and at that end provided with a fixed cross axle or axis E secured removably at its apertured ends e by the removable pins e' extending down through apertures d' in the inner ends of the side 10 bars D D and the apertures e in the ends of the axle E.

F is a slotted segmental or curved sheet-guide secured at the lower edge of its vertical inner wall to the cross axle E, or a 15 bar mounted thereon while the lower edge of its curved portion having the slots f is secured to a horizontal tubular open ended anvil housing G; the outer side of the anvil housing G having a longitudinal slot 20 g across its outer face. Below the slot g the anvil housing G has a horizontal gage or flange g' bolted to a crosspiece a' on the bottom A.

Inwardly from the ends of the anvil housing G extend two side arms g' mounted between their ends on the cross axle E and extending therebeyond and bolted to the inner faces of the side bars D D. These arms g' are provided adjacent to the housing G with stops or lugs g' for guide rods K, K, to be presently described.

H designates a tubular anvil mounted removably in housing G and provided with parallel series of punch apertures h and having its ends closed; one or both of the end closures h' being removable so that the punchings contained within the tubular anvil H may be removed from time to time.

J designates a series of vertically disposed receiving pins secured at their lower ends in any suitable manner to the cross axle E; a clamping bar J' and bolts j being shown in the present instance as securing the pins to the main axle E. The upper ends of the 45 pins J lie adjacent to the upper ends of the slots f in sheet-guide F.

K K are two swinging guide rods mounted on the axle E and at their free ends carrying the sliding crosshead K' provided 50 with a series of punches K² which, when the guide rods K K are swung down into a horizontal position, register with the exposed series of apertures h in the anvil H. The punches K² are roughened or toothed in any suitable manner so as to retain the sheets thereon after being punched.

L is a follower also mounted on the rods K K and having apertures through which the punches K² pass. The follower L has 60 guide pins l l, which extend through crosshead K' and are connected at their outer ends by a handle bar L'. Springs l' l' are interposed between the handle bar L' and crosshead K' for retracting the follower L.

M M are two lever arms mounted on the

ends of axle E and are connected at their outer ends by a handle bar M' and so constitute the main operating lever of the machine.

N N are two links pivoted at their outer ends to the ends of the crosshead K' and at their inner ends are pivoted to the inner ends of the lever arms M M to one side of the axes thereof.

It follows, therefore, that when the lever 75 M M is swung up into a vertical position with the guide rods K K resting on the stops g' of the anvil housing G the punches K² will register with the anvil apertures h. By now placing the sheets with their lower edge 80 upon the horizontal gage g' and between the punches K² and apertures h, and then swinging the lever M M to the left, the crosshead K' will be moved toward the anvil H, and the punches K² will punch the sheets. 85 By now raising the lever M the punches will, through the links N N, be withdrawn from the anvil, but the sheet or sheets will remain on the punches. The operator will now grasp the main lever M with the right 90 hand and the handle bar L' with the left hand. By lifting the handle bar L' the crosshead, punches and sheets carried thereby will be swung up over the curved slotted sheet-guide F, which prevents the sheets 95 from falling and brings their perforations and the punches vertically over the receiving pins J. During this upward movement of the crosshead K' and punches K² the operator will keep moving the lever M to the 100 right out of the way, which causes the punches and leaves to clear the pins.

The handle bar L' will now be pressed down so as to cause the follower L to force the sheet or sheets off of punches K² onto 105 pins J. The crosshead K' may now be swung to the left and down upon the stops g' and hand lever M swung up to a vertical position.

Having thus described how the sheets are 110 perforated and placed upon the pins J, I will now describe the means for clamping the sheets together and removing them in a clamped condition into position for sewing or otherwise securing them together.

O designates a horizontal vertically swinging clamp carrier pivotally connected at its outer or right end to the two side bars D D with its inner end provided with a plate O' having recesses o to straddle the pins J 115 and permit the tongues formed by the recesses to rest on a support along the upper side of the main axle so that as the sheets are strung on the pins J they will rest upon the carrier O and its attached plate O'. 120

The inner corners of the plate O' are cut away to form recesses o² and back of these recesses the sides of the plate O' are provided with beveled or countersunk apertures o³ to receive the depending legs p p of a 125

removable U-shaped clamp P; the outer sides of the legs p p being formed as ratchets to engage the edges of apertures o². The crossbar p' of the clamp has a handle p² and a wide bearing plate p³ projecting toward the pins J when the clamp is in place.

The clamp and sheet carrier O is actuated as follows: Two cams M⁵ extend from the 10 hubs of the lever M and when the lever M is swung down to the right into horizontal position these cams M⁵ project inwardly and downwardly alongside of the ends of the slotted plate O'. This plate O' is provided 15 with two transverse slides R, which, when moved outwardly, will project over the cams M⁵, so that in raising lever M the cams M⁵ will engage the ends of the slides R and so lift the clamp and sheet carrier O and with 20 it the pile of sheets to free the pile from the pins J. When the slides R are retracted stops r r at their ends will cross the recesses o² and so prevent the guide rods K K from 25 swinging too far. That is to say, the stops r r hold the rods K K with the punches K² K² in vertical alinement with the pins J until the said stops are moved outwardly away from the recesses o².

When the clamp P is in place over a pile 30 of sheets S and their covers S' as shown in Fig. 6, and the slides R R have been moved outwardly to project their ends over cams M⁵ and remove their stops r r from recesses o² o², the guide rods K K may be swung 35 into the said recesses, which will cause the crosshead K' and punches K² K² to overlie the flange p² of the clamp P. By now holding the handle bar L' and lifting the lever M the links N will exert a down pull on the 40 crosshead K' and cause the clamp to move down upon the pile of sheets while at the same time the cams M⁵ are lifting the free end of the carrier O toward the descending crosshead and punches and so a double compression is exerted to clamp the pile of 45 sheets upon carrier O. After the sheets have been sufficiently compressed the crosshead K' and the lever M will be moved out of the way and the carrier O with the 50 clamped pile of sheets will be swung up into a vertical position, as shown in Fig. 10.

The form of clamp to be actuated as above described may be varied as desired without departing from the spirit of my invention.

I will now describe the means for operating the slides R R and locking the carrier in its vertical position. The slides R R are provided with longitudinal guide slots r' r', through which are passed headed pins or 55 screws r² r², which hold the slides to the lower face of plate O' and the inner ends of the slides are provided with lugs or ears r³ r³ between which the head t of a rock shaft T works. The rock shaft T extends 60 along the lower side of the swinging carrier

O to the hinged end thereof, and is there provided with a handle t', which projects up through a slot o⁹ in the carrier. By throwing the handle t' rearwardly the head t will be turned flatwise between the lugs 70 or ears r³ passing the center to keep it in position, and so move the slides R outwardly in opposite directions for the purpose herefore described. A bow-spring U serves to 75 press the slides R R inwardly.

In order that the carrier O may be held in its vertical position as shown in Fig. 10, I provide the end crossbar a¹⁰ of the bottom A with a slot a¹¹, into which the handle t' may be turned and where it will be held by 80 the force of the spring U upon the head t at the opposite end of rock shaft T.

With the carrier O thus swung up with the sheets clamped in place the perforations in the pile will be exposed through the recesses o in plate O' so that the needle and cord or other fastening means may be passed through the perforations. Where such sewing is employed to bind the pile of sheets and their covers the projecting portions of 90 plate O' between the recesses o serve to hold the thread in passing from one line of perforations to the other in the pile. The thread in so passing from one set of perforations to the other will be drawn under said 95 projecting portions of plate O' and so be held against the adjacent sheet or leaf.

It will be seen that I have provided a simple, neat and efficient office fixture by means of which it is possible to punch and file the 100 day's correspondence of the largest office as the bills and letters come in and at the same time have the same exposed to view.

In using the device the day's letters accumulated and evened in the triangular box 105 may be punched and transferred to the series of receiving pins J; a back having been first punched and transferred to the pins. At the end of a stated period, say a month, the pins J will have become filled and then 110 a cover is punched and transferred to the pins over the pile of letters or sheets. Then the clamp P will be applied and forced down upon the pile of sheets as just described, after which the carrier O and the 115 clamped pile may be swung up into vertical position with the sheet perforations extending horizontally so as to be in the most convenient position for the passage of a binding cord or other fastening means. The 120 pins B, punches K² and pins J will be correspondingly spaced.

Various modifications may be made in the machine without departing from the spirit 125 of my invention.

What I claim is:

1. In a loose leaf binding machine, the combination with a plurality of receiving pins, of a bodily movable plurality of punches movable in one direction to punch 130

the leaves and then movable in another direction to carry the punched leaves or sheets over the said pins, whereby the leaves or sheets may be moved from the punches to the pins.

2. In a loose leaf binding machine, the combination with a plurality of receiving pins, of a bodily movable plurality of punches, and a normally retracted follower or stripper carried thereby; said punches being movable from the punching position over the pins to bring the punches into alinement therewith to permit the follower or stripper to deposit the punched leaves or sheets upon the pins.

3. In a loose leaf binding machine, the combination with a plurality of receiving pins, of a plurality of punches adapted to be moved into alinement with the pins to permit the punched leaves or sheets to be transferred to the pins, and a sheet guide leading to the pins to hold the leaves or sheets in position.

4. In a loose leaf binding machine, the combination with a crosshead provided with a plurality of punches, swinging guide rods on which the crosshead slides, an operating lever operatively connected with the crosshead, and an anvil for the punches, of a plurality of receiving pins over which the crosshead may be swung to bring the punches into alinement therewith for transferring the leaves or sheets from the punches to the pins.

5. In a loose leaf binding machine, the combination with a crosshead provided with a plurality of punches, swinging guide rods upon which the crosshead slides, an operating lever, links connecting the lever and crosshead, and an anvil to coöperate with the punches, of a plurality of receiving pins over which the crosshead may be swung to bring the punches into alinement therewith, a follower or stripper on the crosshead to transfer the leaves or sheets from the punches to the pins, and a curved guide for the sheets extending from the anvil to the upper ends of said pins.

6. In a loose leaf binding machine, the combination with a crosshead provided with a plurality of punches, swinging guide arms on which the crosshead is mounted to slide, an operating lever to which the crosshead is operatively connected, and an adjustable anvil having series of punch openings adapted to be successively brought into proper relation with the punches, of a plurality of receiving pins over which the crosshead may be swung to bring the punches into alinement therewith.

7. In a loose leaf binding machine, the combination with a tubular anvil having punch openings, and adapted to receive and hold the punchings, and a housing in which the anvil is removably mounted, of a cross-

head having a plurality of punches, means for moving the crosshead and punches toward and from the anvil and a series of vertically disposed pins over which the crosshead may be swung to bring the punches into alinement therewith.

8. In a loose leaf binding machine, the combination with a tubular anvil having a plurality of rows of punch openings, and a tubular longitudinally slotted housing in which the anvil is removably and adjustably mounted, of a crosshead having a plurality of punches, means for moving the crosshead and punches toward and from the anvil and a series of vertically disposed pins over which the crosshead may be swung to bring the punches into alinement therewith.

9. In a loose leaf binding machine, the combination with a tubular anvil having punch receiving openings therethrough and provided with a removable end closure, and a housing in which the tubular anvil is removably mounted, of a plurality of punches coöperating with the anvil, means for operating the punches and a series of vertically disposed pins over which the punches may be swung into alinement therewith.

10. In a loose leaf binding machine, the combination with receiving pins for the punched sheets, of a movable sheet carrier extending to the lower end of the pins to lie under the impaled sheets; said carrier adapted to have the sheets clamped thereto and to be moved upwardly and carry the clamped pile into position for sewing or securing.

11. In a loose leaf binding machine, the combination with receiving pins for the punched sheets and means on which the pins are mounted at one end, of a movable carrier extending to the fixed ends of the pins to lie under the impaled sheets, and an adjustable clamping mechanism on that end of the carrier next to said pins to clamp the pile of sheets thereupon; said carrier adapted to be swung up with the clamped pile of sheets into position for securing or sewing same.

12. In a loose leaf binding machine, the combination with a plurality of pins for the punched sheets and means on which the pins are mounted at one end, of a movable carrier extending at one end alongside the fixed ends of the pins, a clamp bar to extend across the said end of the carrier over the pile of sheets, and adjustable means connecting the ends of the clamp bar with the said carrier to hold the clamp bar upon the pile of sheets.

13. In a loose leaf binding machine, the combination with a plurality of sheet receiving pins and means on which said pins are mounted at one end, of a movable carrier extending at one end alongside the fixed ends of the pins to underlie the impaled sheets, apertures being formed in the sides of the

said end of the carrier, and a clamp bar having ratchet legs working in said apertures; the edges of the apertures being beveled to engage said ratchets.

5 14. In a loose leaf binding machine, the combination with a plurality of sheet receiving pins and means on which the pins are mounted at one end, of a vertically swinging sheet carrier extending at its free end along- 10 side the fixed ends of the pins to underlie the pile of sheets, a clamp for the pile carried by the said free end of the carrier, and means for locking the sheet carrier in its upright position.

15 15. In a loose leaf binding machine, the combination with a plurality of vertically disposed sheet receiving pins, of a vertically swinging sheet carrier notched at its free edge to straddle the lower portions of the 20 pins and underlie the pile of sheets thereon, and an adjustable clamp bar to cross the free end of the said carrier and clamp the pile of sheets thereon.

16. In a loose leaf binding machine, the combination with a plurality of vertically disposed sheet receiving pins, a punching mechanism at one side of the pins including a sliding crosshead provided with punches, a cross axle below the pins, guide rods for 25 the crosshead journaled on said axle, and a lever also journaled on said axle, and operatively connected with the crosshead; said crosshead being movable over the pins with its punches in line therewith, of a vertically swinging sheet carrier extending at its free end across the lower ends of the pins to underlie the pile of sheets, an adjustable clamp for the free end of the said carrier, and means whereby the crosshead may be 35 moved by said lever down upon the clamp and the free end of the sheet carrier simultaneously lifted toward the descending crosshead.

17. In a loose leaf binding machine, the combination with a plurality of vertically arranged sheet receiving pins, a punching mechanism including a sliding crosshead provided with punches, swinging guide rods for the crosshead whereby it may be swung 45 up over the pins to bring its punches in line therewith, and an operating lever having cams and linked to the crosshead, of a vertically swinging sheet carrier extending at its free edge across the lower ends of said 50 pins to underlie the pile of sheets, a clamp bar mounted adjustably on the free end of the carrier; the sheet carrier having recesses in its free edge to permit the guide rods to swing beyond the pins and bring the crosshead over the clamp bar, slides mounted 55 transversely across the under side of the

free end of the swinging carrier and when retracted lying across said recesses, and means for projecting the slides across the cams and at the same time uncovering said 65 recesses; whereby as the cams lift the carrier the crosshead will be moved toward the clamp bar.

18. In a loose leaf binding machine, the combination with a plurality of vertically arranged sheet receiving pins, a crosshead provided with punches and having swinging guide rods whereby it may be swung from its punching position over and beyond the pins, and a swinging operating lever 70 linked to the crosshead and provided with cams at its pivoted end, of a vertically swinging sheet carrier extending at its free edge across the lower ends of the pins and provided with transverse slides on its under 75 side, a rock shaft extending longitudinally along the under side of the carrier provided with a head at its inner end engaging the inner ends of said slides to project the outer ends thereof across the cams; the outer end 80 of the rock shaft having an operating handle, and means whereby the handle serves to lock the carrier when swung up into a vertical position.

19. In a loose leaf binding machine, a 90 three-part casing or box; the middle section being open at its top and bottom and hinged to the rear edge of the lower section, a sheet receiving and evening box held in the said open section and having its sides converging downwardly and inwardly when said section is raised, in combination with a sheet punching mechanism mounted in the lower or base section.

20. The combination with the casing having 100 an upwardly and outwardly swinging section provided with impaling pins, of vertically disposed receiving pins within the lower section and spaced apart to correspond with the first named pins, and a punching 105 mechanism mounted in the lower part of the casing with its punches spaced to correspond with both of said sets of pins.

21. In a loose leaf binding machine, the combination with a crosshead provided with 110 a plurality of punches, swinging guide rods on which the crosshead slides, an operating lever operatively connected with the crosshead, an anvil for the punches, and a gage flange along the anvil for the lower edges 115 of the sheets, of a plurality of receiving pins over which the crosshead may be swung to bring the punches into alignment therewith for transferring the leaves or sheets from the punches to the pins.

In testimony whereof I affix my signature.
HENRY M. CRIPPEN.
